UNITED STATES PATENT OFFICE.

WILLIAM J. DOOLEY, OF NEW YORK, N. Y.

DEVICE FOR OPENING AND CLOSING SLIDING DOORS.

Application filed September 15, 1921. Serial No. 500,987.

To all whom it may concern:

Be it known that I, WILLIAM J. DOOLEY, a citizen of the United States, and a resident of the city of New York, borough of Manhattan, in the county of New York and State of New York, have invented a new and Improved Device for Opening and Closing Sliding Doors, of which the following is a full, clear, and exact description.

This invention has relation to a device for opening or closing sliding doors, and refers more particularly to a device applicable to steel freight car doors, the same to be employed where the door has become jammed or otherwise difficult to move.

The invention contemplates a simple, inexpensive and compact device, readily capable of association or disassociation with the car and door for effectively moving the same to open or closed position with a minimum of effort and without in any way injuring the door or doorway.

With the above recited and other objects in view, the invention resides in the novel construction, combination and arrangement of parts set forth in the following specification, pointed out in the appended claims and illustrated in the accompanying drawings, it being understood that right is reserved to embodiments other than those actually illustrated herein to the full extent indicated by the general meaning of the terms in which the claims are expressed and by variations in the phraseology of the same.

In the drawings—

Figure 1 is a fragmentary side elevation of a car with the device in associated relation for effecting the opening of the door.

Figure 2 is an enlarged fragmentary sectional plan view taken approximately on the line 2—2 of Figure 1.

Figure 3 is an enlarged side view of the device removed.

Figure 4 is an enlarged sectional plan view taken approximately on the line 4—4 of Figure 3.

Referring to the drawings by characters of reference, 10 designates a freight car provided with the usual door opening 11 and sliding door 12 for closing the same, which door is supported by the hangers 13 from a track 14.

The device constituting the invention, which serves as a means for sliding the door to open or closed position when the same

has become jammed, stuck or otherwise difficult to move, comprises a member A adapted to be associated with the door, which member includes a rectangular frame 60 15 having mounted transversely therein a drum shaft 16 in the bearings 17. A drum 18 is secured on the medial portion of the drum shaft for rotation therewith, while the opposite extremities of the drum shaft 65 extend outwardly from the bearings 17 and are provided with oppositely disposed sets of ratchet teeth 19 and 20, which are designed to coact with the a pawl 21 pivotally mounted as at 22 in the head 23 of a manipulating lever 24. The head 23 is provided with a transverse opening 25 of a diameter to snugly receive the extremities of the drum shaft 16. The pawl 21 is normally forced 70 into engagement with the teeth of the ratchets by a spring 26, whereby the manipulating lever will operate to turn the drum and drum shaft in one direction, while the same will freely move in the opposite direction to obtain a new purchase on the 75 ratchet teeth. By associating the manipulating lever with the opposite extremities of the drum shaft, rotation of the drum shaft in opposite directions may be effected. The member A is especially designed to 80 coact with a steel car door of a type which includes at its opposite ends a channeled flange 12^a, into which one extremity of the rectangular frame is insertable. In order 85 to hold the member A against casual displacement, the upper and lower side rails of the frame adjacent one end are provided with inclined notches 27, into which wedges 28 are driven to coact with the channeled flange 12^a and the inclined walls of the notches 90 to frictionally retain the member A in place. The device further includes a flexible element 29, such as a cable or rope, which is anchored at one extremity 30 to 95 an apertured bracket 31 on the car or door support. The opposite free end of the cable 29 is wound about the drum with its free terminal extending in the opposite direction from its anchored terminal. To 100 effect the opening or closing of the door, the manipulating lever 24 is actuated to rotate the drum in a direction opposite the direction of travel of the door, thereby winding new convolutions in that portion 105 of the cable lying between the anchored terminal and the drum and unwinding that portion of the cable between its free ter- 110

5 minal and the drum, which free terminal is held by the operator. This operation will serve to advance the member A toward the anchored terminal of the cable and the member A due to its engagement with the channelled flange 12^a of the door, will effect the opening or closing of the door without injury to the door or door support.

10 It will thus be seen that a simple and compact device has been devised which will positively effect movement of the door and which is readily applicable to and removable from the car.

I claim:

- 15 1. A portable device for facilitating the opening and closing of sliding doors comprising a pair of interengageable members, means for detachably securing said members respectively to a door and door support, 20 manipulating means at the point of interengagement of said members for effecting the advancement of the door toward the member secured to the door support, one of said members comprising a flexible element, and means at one extremity thereof for detachably securing the same to the door support, the other of said members consisting of a frame, means for detachably securing the same to the door, a drum rotatably 25 mounted in said frame and adapted to have wound thereon the free extremity of the

flexible element, and means for manipulating said drum to effect the rotation thereof and winding of the flexible element thereon.

2. The combination with a door support 35 having a door opening therethrough and a sliding door mounted for association therewith and provided with a channelled flange at its forward edge, of a detachable device for moving the door to covering or uncovering position with respect to the door opening, including a member adapted to be associated with the door, said member comprising a frame provided at its forward edge with upper and lower inclined notches, 40 said notched forward edge being adapted to underlie the channelled flange at the forward edge of the door, wedges insertable within said notches for anchoring the frame in place, a rotary drum mounted in the 45 frame, means for manipulating said drum to rotate the same, and a second member consisting of a cable, means for anchoring one extremity of said cable to the frame support, said cable having a portion thereof 50 coiled about the drum whereby upon rotation of the drum the cable will coact therewith to advance the first member together with the door toward the anchored end of the cable.

WILLIAM J. DOOLEY.
